UNITED STATES PATENT OFFICE.

WALLACE B. MARTIN, OF ST. PAUL, MINNESOTA.

VALVE GRINDING AND RESEATING TOOL.

1,286,378.

Specification of Letters Patent.

Patented Dec. 3, 1918.

Application filed April 6, 1917. Serial No. 160,153.

To all whom it may concern:

Be it known that I, WALLACE B. MARTIN, a citizen of the United States, residing at St. Paul, in the county of Ramsey and State 5 of Minnesota, have invented certain new and useful Improvements in Valve Grinding and Reseating Tools; and I do hereby declare the following to be a full, clear, and exact description of the invention, such as will enable others skilled in the art to which it 10 pertains to make and use the same.

My invention relates to valve grinding and reseating tools; and, to this end, it consists of the novel devices and combinations 15 of devices hereinafter described and defined in the claims.

In the accompanying drawings, which illustrate the invention, like characters indicate like parts throughout the several 20 views.

Referring to the drawings,

Figure 1 is a fragmentary plan view of an internal combustion engine to which is secured, in working position, the improved 25 tool, some parts being shown in different positions by means of broken lines;

Fig. 2 is a fragmentary view, partly in plan and partly in horizontal section of the tool and the cylinder casting, on an enlarged 30 scale; and

Fig. 3 is a view, principally in side elevation with some parts sectioned on the line 3-3 of Fig. 2.

For the purpose of illustrating the valve 35 grinding and reseating tool in operative position, there is illustrated in the drawings an internal combustion engine, of the "Ford" type. Of the parts of the engine illustrated, the numeral 7 indicates the cylinder cast- 40 ing having therein cylinders 8, valves 10 and seats 9 for said valves. The cylinder head 11 is detachably secured by bolts 12 in position on the casting 7. It is important to note that the bolts 12 extend loosely through 45 bolt holes in the cylinder head 11 and their ends have screw-threaded engagement with bolt holes 13 in the cylinder casting 7. It will also be noted, there is one of these bolt holes 13 located equi-distant between each

pair of valve seats 9. In the top of each 50 valve 10, is a pair of diametrically opposite wrench pin holes 14.

Referring now in detail to the invention, the numeral 15 indicates a cast bearing head comprising upper and lower plates connected by a centrally located web. In the rear end of the bearing head 15, is a bore which extends completely through both plates thereof and affords a seat 16, and likewise, there is a bore in the front end of said head 55 which affords a seat 17. Extending through the seat 16, is a supporting rod 18, on which the bearing head 15 is free to swing laterally and move upward or downward thereon. As shown, the supporting rod 18 is in the 60 form of a headed bolt, of the same diameter as one of the bolts 12, and has screw-threads of the same pitch. Preferably, one of the bolts 12, removed from the cylinder head 11, is used for the supporting rod 18. 65 Placed on the screw-threaded end of the supporting rod 18, is a nut which acts as a stop shoulder 19. The supporting rod 18 is rigidly secured to the casting 7 by screwing the same into the bolt hole 13 between a pair 70 of the valve seats 9 that are to be ground.

To rigidly hold the bearing head 15 against lateral swinging movement with its seat 17 axially alined over either one of the respective seats 9, there is provided an anchor pin 20. This anchor pin 20 is arranged to project through either one of two holes 21 formed in ears 22 on the longitudinal edges of the lower plate of the bearing 15 and are located equi-distant from the axis of 85 the supporting rod 18. The anchor pin 20 is upwardly tapered and also affords a support for the bearing head 15 and holds the same clear of the shoulder 19. Integrally formed with the anchor pin 20, is a base 23 90 which rests directly on the top of the cylinder casting 7 and is provided with a hole 24 through which the supporting rod 18 is loosely inserted before the same is secured into one of the bolt holes 13. In screwing 95 the supporting rod 18 into one of the bolt holes 13, the shoulder 19 thereon engages the base 23 and securely clamps the same onto

the cylinder casting 7 with the anchor pin 20 positioned equi-distant between the respective pair of valves 10.

A tubular spindle 25 is mounted in the 5 seat 17 of the bearing head 15, for both rotary and endwise movements, and has a hand crank 26 secured to its upper end by a transverse pin 27. Extending axially through the tubular spindle 25, is a stem 28 having on its lower end, below said spindle, a valve grapple in the form of a fork 29, the prongs of which are arranged to enter the pin holes 14 in any one of the valves 10. The upper end of the stem 28 is 10 expanded to afford a bearing 30 through which the pin 27 extends and supports the valve grapple 29 for common rotation with the 15 tubular spindle 25 but with freedom for lateral wobble motion. The bearing 30 engages the internal wall of the tubular spindle 25 and holds the upper end of the stem 28 against lateral movement and is rounded to permit free universal lateral wobble movement of the valve grapple 29. Integrally formed with the bearing 30 and forming an upward extension of the stem 28, is a finger piece 31. This finger piece 31 projects above the tubular spindle 25 and affords means by which the valve grapple 29 20 may be guided into the pin holes 14 of one of the valves 10.

To grind a valve in its seat with the improved tool, it is only necessary to operate the crank 26, it, of course, being understood 35 that before the grinding takes place, a suitable abrasive is applied to the surfaces of the valve and its seat to be ground. In grinding a valve, sufficient pressure, to cause the abrasive to cut, is applied by an inward 40 pressure on the crank 26, while turning the same. With the valve grapple 29 mounted with freedom for universal lateral wobble motion, a valve is ground true in its seat, for the reason that there is no lateral pressure on the valve tending to grind its seat 45 into an oblong form. After one valve of a given pair is ground, the other one thereof may be ground by raising the bearing head 15 to carry the same out of contact of 50 the anchor pin 20 and then move the same laterally and inward to carry the anchor pin 20 into the respective hole 21 and thereby securely hold said bearing head with the valve grapple properly positioned over the 55 respective valve to be ground. As previously stated, the prongs of the valve grapple are guided into the pin seats 14 by means of the finger piece 31.

The above described valve-grinding and 60 reseating tool, while extremely simple and of comparatively small cost to manufacture, has, in actual usage, proven highly efficient for the purpose had in view. It is also evident that the tool may be very quickly applied to or removed from a cylinder cast-

ing, or when applied to a cylinder, shifted from one valve to the other of a given pair. As the tool is very compact, the same, when not in use, will occupy very little space in the tool box.

In place of the valve grapple 29, the stem 28 may be provided with a valve seat-forming device or cutter, by the use of which a valve seat may be reformed. This device may be in the form of a separate tool, or the 70 tool may be provided with interchangeable stems equipped, the one with a valve grapple and the other with a valve seat-forming device. The wobble motion in the tool is, of course, just as important in the valve 75 seat-forming device as it is in the valve grapple.

What I claim is:

1. A valve-grinding tool comprising a bearing head, a tubular spindle rotatively 85 mounted in the bearing head with freedom for bodily movement toward and from the work, means for rotating the spindle, and a valve-grapple having a stem extending into the spindle and secured thereto for common 90 movements therewith and with freedom to permit universal lateral wobble movement of the grapple stem therein.

2. A valve-seating tool comprising a rigidly held support having a swinging bearing head, driving means rotatively mounted in the bearing head with freedom for bodily movement toward and from the work, and a valve seat-forming device secured to the 95 driving means for common movements therewith and with freedom for universal lateral wobble movement with respect to the work.

3. A valve-grinding tool comprising a supporting rod, a bearing head mounted on said 105 rod for lateral swinging movement over several valves, a valve grapple carried by said bearing head, and means for anchoring said bearing head in predetermined positions with the valve grapple positioned over any 110 one of the valves.

4. A valve-grinding tool comprising an anchor having a supporting rod and a stud, a bearing head mounted on said rod for axial and lateral swinging movements thereon 115 over several valves, a valve grapple carried by the bearing head, said bearing head having several bores any one of which may be brought into interlocking engagement with said stub, by lateral swinging and axial 120 movements of the bearing head on the supporting rod, for positioning the valve grapple over any one of the valves, and means for operating the valve grapple.

5. A valve-grinding tool comprising an 125 anchor having a supporting rod and a tapered stud, a bearing head mounted on said rod for axial and lateral swinging movements thereon over several valves, a valve grapple carried by the bearing head, 130

said bearing head having several bores any one of which may be brought into interlocking engagement with said stub, by lateral swinging and axial movements of the bearing head on the supporting rod, for positioning the valve grapple over any one of the valves, said tapered pin also affording a support for the bearing head when extending into one of the bores thereof, and 10 means for operating the valve grapple.

6. A portable valve-seating tool comprising a fixed support, a bearing head mounted

on the support for lateral swinging movement over several valves, and a valve seat-forming device carried by the bearing head 15 with freedom for endwise and universal lateral wobble movements.

In testimony whereof I affix my signature in presence of two witnesses.

WALLACE B. MARTIN.
